(57) **CLAIM**

We claim the ornamental design for a “radar detector”, as shown and described above.

DESCRIPTION

FIG. 1 is a top view of a radar detector;
FIG. 2 is a side view of the radar detector;
FIG. 3 is a side view of the radar detector;
FIG. 4 is a front view of the radar detector;
FIG. 5 is a rear view of the radar detector;
FIG. 6 is a bottom view of the radar detector;
FIG. 7 is a perspective view of the radar detector; and,
FIG. 8 is a perspective view of the radar detector.
